UNITED STATES PATENT OFFICE.

EDGAR H. COTTRELL, OF WESTERLY, RHODE ISLAND.

NEWSPAPER.

1,126,405.

Specification of Letters Patent.

Patented Jan. 26, 1915.

Application filed April 1, 1913. Serial No. 758,946.

To all whom it may concern:

Be it known that I, EDGAR H. COTTRELL, a citizen of the United States, and resident of Westerly, in the county of Washington and State of Rhode Island, have invented a new and useful Improvement in Newspapers, of which the following is a specification.

In newspapers where the pages are approximately from sixteen to eighteen inches wide and twenty-one to twenty-three inches long and the sheets are folded parallel with the columns of printed matter, it is well known that because of the very large size of the leaves, the location of the fold, and the poor quality of the paper used, it is extremely difficult to properly handle the paper because of the tendency of the free portions of the leaves above the point held at one side of the paper to fall over. This tendency is extended to both sides of the paper when the paper is unfolded. Furthermore, it is well known that when the paper is unfolded it is extremely difficult, awkward and tiresome to properly hold the same for perusal and that it is also very difficult to fold back a leaf because of the tendency of the leaf to fall over by gravity in the wrong direction and because of the large size of the leaf.

The object of my invention is to overcome the above defects and disadvantages by providing a newspaper which shall have its leaves secured together along a line transversely through the middle of the printed page, said newspaper being provided with a fold along said line. This arrangement renders the newspaper very convenient for handling and reading, the newspaper being at all times kept within a reasonable size.

A further useful feature of my invention is the arrangement of the printed matter whereby the paper may be read from beginning to end by turning the leaves over successively in the same direction.

Practical embodiments of my invention are represented in the accompanying drawings, in which—

Figure 1 is a front view of one form of my invention with the lower right hand corners of the leaves folded over to illustrate the reverse arrangement of the printed matter on the back page to that on the front page, Fig. 2 is a face view of the newspaper with the lower half of the first

leaf turned over to show the arrangement of the printed matter on the second page, the lower right hand corner of the third leaf being also shown turned over to illustrate the arrangement of the printed matter on page 3, Fig. 3 is a front view of a newspaper showing a second form of my invention in which a space is left through the printed matter along the fold, the lower right hand corners of the leaves being turned over, and Fig. 4 is a face view of this form exhibiting page 2 and a portion of the leaf turned over to exhibit part of page 3.

In the form shown in Figs. 1 and 2, no decided space is left across the pages along the fold, while in Figs. 3 and 4 a decided space is left along the fold and on the interior pages a heading is provided for the lower half of the page. The newspaper in both of these forms is shown as having its leaves secured together along a line transversely through the middle of the printed pages and the newspaper is provided with a fold along said line. The front printed page is printed on the front side of one leaf and the back printed page is printed on the back side of the last leaf. The intermediate pages are each printed partly on one leaf and partly on another leaf. The arrangement of the printed matter is such that the newspaper may be read from beginning to end by turning the leaves over successively in the same direction. To accomplish this result, the back page is printed in the reverse direction to the front page and the printed matter of each of the intermediate pages is printed in the same direction, the printed matter on succeeding leaves being printed alternately in reverse directions.

By the arrangement of the printed matter and folding and securing the leaves as above described, I am enabled to produce a newspaper which may be very readily handled and read.

By the term "newspaper" I wish to include all large products of an equivalent nature where the size of the product renders the same open to the disadvantages and defects enumerated if they were printed and folded as heretofore and in which such disadvantages and defects would be remedied by the printing and folding of the same in the manner substantially as herein shown and described. By the term "page"

as used herein, I mean the largest printed surface which can be exposed at one time to the eye of the reader, whether printed on one sheet as is each of the front and back 5 pages or printed on two sheets as is each of the remaining pages.

What I claim is:—

1. A newspaper comprising a plurality of assembled printed sheets having one page 10 printed on one side of one sheet, another page printed on one side of another sheet and the remaining pages each printed partly on one sheet and partly on another sheet.
2. A newspaper comprising a plurality of 15 assembled printed sheets having one page printed on one side of one sheet, another page printed on one side of another sheet and the remaining pages each printed partly on one sheet and partly on another sheet, the sheets being folded transversely across the 20 middle of their printed pages.
3. A newspaper comprising a plurality of assembled printed sheets having one page 25 printed on one side of one sheet, another page printed on one side of another sheet and the remaining pages each printed partly on one sheet and partly on another sheet, the sheets being secured together transversely across the middle of their 30 printed pages.
4. A newspaper comprising a plurality of assembled printed sheets having one page 35 printed on one side of one sheet, another page printed on one side of another sheet and the remaining pages each printed partly on one sheet and partly on another sheet, the sheets being folded and secured together transversely across the middle of their 40 printed pages.
5. A newspaper comprising a plurality of assembled printed sheets having one page 45 printed on one side of one sheet, another page printed on one side of another sheet and the remaining pages each printed partly on one sheet and partly on another sheet, the printed matter on the front sides of all of the sheets reading in one direction and the printed matter on the back sides of all of the sheets reading in the reverse direction, whereby the newspaper may be read from 50 beginning to end by turning the leaves over successively in the same direction, the sheets 55 being folded and secured together transversely across the middle of their printed pages.
6. A newspaper comprising a plurality of 60 assembled printed sheets having one page 65 printed on one side of one sheet, another page printed on one side of another sheet and the remaining pages each printed partly on one sheet and partly on another sheet, the printed matter on the front sides of all of the sheets reading in one direction and the 70 printed matter on the back sides of all of the sheets reading in the reverse direction, whereby the newspaper may be read from beginning to end by turning the leaves over successively in the same direction, the sheets 75 being folded transversely across the middle of their printed pages.
7. A newspaper comprising a plurality of assembled printed sheets having one page 80 printed on one side of one sheet, another page printed on one side of another sheet and the remaining pages each printed partly on one sheet and partly on another sheet, the printed matter on the front sides of all of the sheets reading in one direction and the 85 printed matter on the back sides of all of the sheets reading in the reverse direction, whereby the newspaper may be read from beginning to end by turning the leaves over successively in the same direction, the sheets 90 being secured together transversely across the middle of their printed pages.
8. A newspaper comprising a plurality of assembled printed sheets having one page 95 printed on one side of one sheet, another page printed on one side of another sheet and the remaining pages each printed partly on one sheet and partly on another sheet, the printed matter on the front sides of all of the sheets reading in one direction and the printed matter on the back sides of all of the sheets reading in the reverse direction, whereby the newspaper may be read from beginning to end by turning the leaves over successively in the same direction, the sheets 100 being folded and secured together transversely across the middle of their printed pages.

assembled printed sheets having one page printed on one side of one sheet, another 55 page printed on one side of another sheet and the remaining pages each printed partly on one sheet and partly on another sheet, the printed matter on the front sides of all of the sheets reading in one direction and the 60 printed matter on the back sides of all of the sheets reading in the reverse direction, whereby the newspaper may be read from beginning to end by turning the leaves over successively in the same direction, the sheets 65 being folded transversely across the middle of their printed pages.

7. A newspaper comprising a plurality of assembled printed sheets having one page 70 printed on one side of one sheet, another page printed on one side of another sheet and the remaining pages each printed partly on one sheet and partly on another sheet, the printed matter on the front sides of all of the sheets reading in one direction and the 75 printed matter on the back sides of all of the sheets reading in the reverse direction, whereby the newspaper may be read from beginning to end by turning the leaves over successively in the same direction, the sheets 80 being secured together transversely across the middle of their printed pages.

8. A newspaper comprising a plurality of assembled printed sheets having one page 85 printed on one side of one sheet, another page printed on one side of another sheet and the remaining pages each printed partly on one sheet and partly on another sheet, the printed matter on the front sides of all of the sheets reading in one direction and the 90 printed matter on the back sides of all of the sheets reading in the reverse direction, whereby the newspaper may be read from beginning to end by turning the leaves over successively in the same direction, the sheets 95 being folded and secured together transversely across the middle of their printed pages.

In testimony that I claim the foregoing as my invention, I have signed my name in 100 presence of two witnesses, this 27th day of March 1913.

EDGAR H. COTTRELL.
